UNITED STATES PATENT OFFICE.

ALEXANDER BOYNTON, OF SAN ANTONIO, TEXAS.

POLISHED-ROD ROTATOR.

Application filed June 19, 1926. Serial No. 117,196.

This invention relates to polished rod rotors especially adapted for use in connection with pumping equipment for wells.

Briefly stated one of the aims of the invention is to provide a polished rod rotor having reliable means by which back strain in the rods as a result of sticking of the cups or plunger is prevented from twisting the rods in two.

Another object is to provide a polished rod rotor having simple means to intermittently turn the polished and pump rods to distribute the wear on the various parts of the pump, the stuffing box and the polished rod, and to keep the joints of the rods tight.

A further and equally important object of the invention is to provide a polished rod rotator which may be easily applied to the pumping equipment without elaborate alteration thereof and without the exercise of unusual skill and which when installed will require little if any attention.

Other objects and advantages will be apparent during the course of the following description.

In the accompanying drawing forming a part of this application and in which like numerals are employed to designate like parts throughout the same,

Figure 1 is a side elevation of the improved polished rod rotator applied;

Figure 2 is a plan view of the improved polished rod rotator;

Figure 3 is a detail sectional view illustrating a lubricator cup and washer.

In the drawing, wherein for the purpose of illustration is shown a preferred embodiment of the invention, the numeral 5 designates a polished rod which may be connected to a beam 6 through the medium of a cross-head 7 in the usual and well known manner so that the rocking of the beam 6 will result in the reciprocation of the rod.

As stated in the objects, the invention is designed to intermittently turn the polished rod 5 to avoid excessive wear on the cups and other parts of the pump as well as stuffing box and polished rod, and to keep the joints of the rods from parting and to this end I have mounted a ratchet wheel 8 on the polished rod at a point above the cross-head 7 and provided means whereby the ratchet wheel may be intermittently rotated as a result of the rocking of the beam. Figure 1 clearly illustrates that the hub 10 of

the ratchet wheel extends on opposite sides of the ratchet wheel and is secured in place on the polished rod by set screws 11 or other suitable fastening devices.

Excessive friction between the hub of the ratchet wheel and the top of the crosshead is avoided by the employment of a washer 14, which, as shown in Figure 3, is positioned in a cup 15, the parts 14 and 15 being positioned between the hub 10 and the top of the crosshead. Oil may be periodically introduced into the cup 15 to lubricate the washer 14 so that the turning of the ratchet wheel will not result in excessive wear on the parts that carry the rotating load.

Figure 1 illustrates that a polished rod clamp 16 is secured on the polished rod immediately above the hub 10 and constitutes a support for a hood 15, the top of which slopes to shed rain, water, ice, and the like, which would otherwise lodge on the ratchet wheel and possibly fill some of the teeth of the same with the result that the operation of the rotator would be more or less interrupted or interfered with.

The teeth of the ratchet wheels are located on the upper side of the wheel and are engaged by the downwardly curved and somewhat pointed terminal portion of a pawl 20 pivotally connected as indicated at 21 to the upper portion of an actuating arm 22. Figure 1 clearly illustrates that a series of openings in the upper portion of the arm 22 provide for the adjustment of the pawl with respect to the arm, for the purpose of regulating the actuation.

The lower portion of the arm 22 is threaded into a boss 26 formed on the upper side of an attaching plate 27. U bolts 28 or other suitable fastening devices may be employed to secure the attaching plate to the beam as shown.

In carrying out the invention, the arm 22 is secured in an adjusted position by means of a jam nut 30 and should it be desired to move the curved end of the pawl radially for varying the extent of rotation of the rod 5, each time the same descends the jam nut 30 is loosened and the pawl is moved either inwardly or outwardly, after which the jam nut is tightened to securely hold the parts in adjusted position. This constitutes the second method of regulating the amount of actuation.

Referring to Figure 2, it will be observed

that the ratchet wheel 8 is provided with a peripheral flange which constitutes a stop by means of which outward movement of the pawl is limited. This prevents the pawl 5 from riding off the ratchet wheel in the event of maladjustment.

A polished rod rotator constructed in accordance with this invention may be applied to the polished rod without disconnecting the 10 well and without altering the construction of any of the parts of the pumping equipment and when applied will intermittently turn the ratchet wheel to bring about uniform wear on the cups, the liner of the working barrel, 15 etc., whereby the life of the parts below the surface is greatly increased, this feature overcoming the necessity of frequently pulling the rods.

As suggested in the opening paragraphs 20 of this specification the rotor has a clutch action by which excessive back strain in the rods as a result of sticking of the cups or plunger is relieved so that the rods may not be twisted in two. In explaining this it is 25 pointed out that the hub 10 turns on the washer 14 only in a clockwise direction as long as the cups or plunger, as the case may be, are free to be turned. When the cups are 30 there is nothing of consequence to induce counter-clockwise turning of the member 10.

However, should the cups or plunger stick 35 in the working barrel a back twist will be built up in the rods, and this back twist will finally overcome the friction between the members 10 and 14 and cause the member 10 to turn in a counter-clockwise direction during the back stroke of the actuator arm 20. It will therefore be seen that the members 40 10 and 14 form a friction clutch by which

the rotor is prevented from twisting the rods in two should the cups stick.

A rotor constructed in accordance with this invention results in the more economical and efficient operation of a pumping well, 45 as cutting of the oil by the use of bad cups, plungers, liners, and working barrels is prevented and maximum production is assured since formation of squirt grooves or jets is overcome. 50

Having thus described the invention, what is claimed is:

1. A polished rod rotor comprising an attaching member having beam engaging means, an upright actuating arm threadedly and adjustably connected to said attaching member, a locking device securing said upright arm in an adjusted position, a pawl 55 adjustably connected to said arm, and a ratchet wheel having radial teeth engaged by said pawl, the adjustable threaded connection between said arm and base forming a means whereby the pawl may be adjusted radially on said wheel. 60

2. A polished rod rotor comprising an attaching member having beam engaging means, an upright actuating arm threadedly and adjustably connected to said attaching member, a locking device securing said upright arm in an adjusted position, a pawl 70 adjustably connected to said arm, and a ratchet wheel having radial teeth engaged by said pawl, the adjustable threaded connection between said arm and base forming a means whereby the pawl may be adjusted 75 radially on said wheel, said ratchet wheel being provided with a peripheral stop flange.

In testimony whereof I affix my signature.

ALEXANDER BOYNTON.
